(57) CLAIM

The ornamental design for a medical gown, as shown and described.

DESCRIPTION

FIG. 1 is a front elevation view of a medical gown illustrating our new design, with the medical gown in an untied configuration; and

FIG. 2 is a rear elevation view thereof.

FIG. 3 is a rear elevation view of a figure wearing a medical gown illustrating our new design in an untied configuration; and

FIG. 4 is a rear elevation view of the figure of FIG. 3 wearing the medical gown of FIG. 4 in the tied configuration.

FIG. 5 is a front elevation view of a medical gown illustrating our new design, with the medical gown in an untied configuration; and

FIG. 6 is a rear elevation view thereof.

FIG. 7 is a rear elevation view of another figure wearing a medical gown illustrating our new design in an untied configuration; and,

FIG. 8 is a rear elevation view of the figure of FIG. 7 wearing the medical gown of FIG. 8 in the tied configuration.

All broken lines showing parts of the drawings are included for the purpose of illustrating use and environment and form no part of the claimed design, with the following exception: the dashed line between the neck and opening along the back of the gown is a perforation.
